UNITED STATES PATENT OFFICE.

RUDOLF WASSERMAN, OF NEW YORK, N. Y.

SKIRT MARKER.

Application filed August 17, 1921. Serial No. 492,955.

To all whom it may concern:

Be it known that I, RUDOLF WASSERMAN, a citizen of the United States, and resident of New York city, in the county of New York and State of New York, have invented certain new and useful Improvements in Skirt Markers, of which the following is a specification.

My present invention relates to skirt markers and more especially to skirt markers of the type designed for self-use by persons fitting their own skirts, and also for convenient use by tailors and dress-makers.

It is an object of the invention to provide a practical skirt marker of simple and inexpensive construction, the use of which shall not tire the operator, and which more particularly shall obviate the need for bending down.

In the preferred embodiment, the apparatus is of the type in which the mark is effected by the ejection of powdered chalk through a nozzle and in the application of the invention to this type of apparatus, it is another object to avoid fatiguing of the hand in operation, and particularly to readily effect a sharp and distinct line without the need for grasping and repeatedly compressing a pneumatic bulb. In the preferred embodiment, the powdered chalk is enclosed in a flexible reservoir such as a pneumatic rubber bulb adjacent or in proximity to the nozzle, the pressure upon the bulb being effected preferably through a plunger of sufficient length to be conveniently operated by downward manual pressure.

According to another feature, a simple casing unit is provided enclosing the powder containing bulb and having formed integrally therewith the nozzle through which the powder for making the mark is ejected, a conduit connecting the mouth of the bulb to the nozzle.

In the accompanying drawings in which is shown one or more of various possible embodiments of the several features of this invention,

Fig. 1 is a perspective view of one embodiment of the invention, illustrating the mode of operating the same,

Fig. 2 is a view in longitudinal cross-section of Fig. 1,

Fig. 3 is a transverse sectional view taken along the line 3—3 of Fig. 2,

Fig. 4 is a perspective view of a modified form of the invention,

Fig. 5 is a view in longitudinal section taken along the line 5—5 of Fig. 6, and;

Fig. 6 is a top view of one of the preferred forms of marking units.

Referring now to the drawings, and particularly to Figs. 1, 2 and 3, I have shown a skirt marker comprising a base 1 preferably hollow and weighted with plaster of Paris as at 2 and including an integral ferrule 3 for retaining the upstanding frame structure of the device. This structure comprises preferably an ordinary yard stick 4

having secured to a face thereof by any desired means the base 5 of a rectangular bar 6 having a longitudinally extending groove 23. Adjustably secured to the frame is the marking unit which in the present embodiment comprises a casing 7 preferably of sheet metal having an extension 8 fitted about the frame and slideable therewith and carrying a clamping lever 9 having an eccentric conformation 10 by which the marking unit can be clamped in desired position upon the frame. The casing 7 has vertical sides 11 each tapering to an apex 12, and a horizontal top 13 integral therewith connects said sides, there being formed integrally with the top and connected with the apices of the sides a small nozzle tube 14 extending along the forward edge of the top and having a longitudinal slit 15. The top 13 of the casing has preferably an integral downward extension 16 with an integral forwardly extending reaction plate

or support element 17 upon which rests preferably a pneumatic rubber bulb 18 containing powdered chalk 19. The mouth of the bulb 18 is connected by a conduit 21 extending preferably on the exterior of the casing to one end of the tube 14, the other end of said tube being closed as at 22. Slidably fitting in the groove 23 of the U-bar 100 there is a plunger rod 24 guided at its upper end by a ferrule 25 on the frame and guided by the ferrule 3 at its lower end.

The plunger has an operating knob 26 at its top and carries intermediate its ends a presser comprising preferably a sheet metal stamping 27 extending at its lower end through a slit 28 in the top of the marker

casing and having a rounded end formed preferably by a ferrule 29 enclosing the lower edge of the blank and engaging the top of the bulb 18. The presser is preferably adjustably secured to the rod by means of a sleeve 30 encircling the rod and having a lateral nipple 31 extending through an aperture in the presser blank 27, a nut 32 threaded upon the nipple serving to clamp the presser in position upon the plunger. A set screw 33 is threaded through the center of the nipple and clamps the sleeve against the rod. The bottom or reaction plate 17 upon which the bulb 18 rests is preferably formed with a longitudinal trough 34 symmetrical with respect to the operative end of the presser and of width materially smaller than the diameter of the bulb.
- 10 Preferably the ferrule 29 at the end of the presser has a short extension 35 beyond the slot 28 preventing the accidental removal of the presser from the slot in the process of adjustment.
- 15 25 Near the upper end preferably a coil spring 36 encircles the plunger rod and is secured at one end to the frame structure as at 37 and at the other end to the plunger as at 38 to maintain it in the upper or raised position shown in Fig. 2. The upper edge 39 of the clamping end of the marking unit, which travels directly over the scale on the frame, is preferably in alignment with the nozzle slot 15 so that the elevation of the nozzle from the floor will be indicated by the position of said edge 39 with respect to the scale.
- 20 To adjust the marker in desired elevation, the set screw 33 and the clamp 9 are both loosened; the marking unit 7 is moved up or down until the edge 39 is at the scale marking indicating the elevation desired, the presser 27 being moved up or down with the marker until the desired position is reached, whereupon the set screw 33 and the clamp 9 are tightened. The marker is then placed upon the floor with the nozzle 15 against the skirt, and by a simple pressure preferably a gentle slap with the palm of the hand upon the knob 26, a sharp and clear chalk line will be produced upon the skirt at the desired elevation. It will be seen that the depression of the plunger against spring 36 caused by the manual pressure urges the edge 29 of the presser 27 against the bulb, pressing the major part thereof into the groove 34, thus forcefully ejecting the air which blows a small quantity of chalk out of the bulb through the conduit 21 into the tube, the chalk emerging through the slit 15, thus forming the desired mark. As soon as the hand is removed from the knob, the spring 36 restores the plunger to raised position and 60 air enters through slit 15 to again restore

the bulb to expanded state. This operation may be repeated, the person slowly turning and depressing the knob at intervals in order to produce a continuous chalk line about the skirt.

70 In Figs. 4, 5 and 6 is shown a modified form of the invention which is even simpler than that of Figs. 1, 2 and 3. Those elements that are common to the two embodiments are designated by the same reference characters. This embodiment comprises a piece of an ordinary yard stick 40 of sufficient length to cover the range required in practice, a strap 41 near the upper end of said stick encircling an operating bar 42 75 which may be an ordinary stick of the general dimensions of a yard stick. Adjustably clamped with respect to the lower stick may be the unit described in connection with Figs. 1, 2 and 3. The presser in 80 the specific embodiment shown comprises a sheet metal blank 43 secured by screws as at 44 to the lower end of the operating bar 42 and extending at its forward end through a slot 45 in the top 46 of the marker casing 85 and having a forwardly extending toe 47 in surface contact with the bulb.

90 In the specific embodiment shown, the casing is formed with an integral rectangular sleeve 48 encircling the yard stick 40 and a set screw 49 extending through the rear surface 50 of said sleeve for clamping the casing in any desired position on the yard stick. In this embodiment, the casing is shown with a flat bottom 51 and a bent-over forward edge 52 extending upwardly therefrom, it being understood that the flat toe 47 of the presser will exert pressure upon the bulb through a sufficient area to effectively compress the same, without likelihood of lateral deflection of the bulb away from the presser. If desired, of course, the groove 34 shown in Fig. 2 may be employed.

95 100 105 The upper rear edge 53 of the casing, as in the other embodiment is aligned with the slit 15 of the nozzle, so that the elevation of the nozzle in this case will also be determined by the reading of said edge upon the yard stick.

110 115 120 In operation, assuming the marker unit to have been set in proper position as in the case previously described, the lower end of the yard stick is placed upon the floor and the unit held vertically with the nozzle 15 in close proximity to the skirt and the upper bar 42 is simply pressed downwardly, compressing the bulb 18 to cause the ejection of powder 19 from the nozzle against the skirt. When the pressure of the hand is released, the bulb rapidly expands by intake of air, raising the presser toe 47 and with it the light operating bar 42 to the home position indicated in Figs. 4 and 5, whereupon the operation may be repeated.

125 130 The construction of Figs. 4, 5 and 6 is

particularly simple involving merely two sticks, both of which may be yard sticks, if desired, or one of which may be an ordinary stick without graduations held in slidale 5 relation with respect to each other by a simple strap 41, a simple sheet metal presser 43 being secured to the upper of said bars and the inexpensive metal casing enclosing the rubber bulb being adjustably secured to 10 the other, the return of the parts to their original position after operation being effected by the bulb without the need for a return spring. Obviously, the metallic parts of this form of skirt marker, may be sold or 15 distributed apart from the yard sticks to dressmakers, tailors or housekeepers to be attached to such yard sticks, as required.

It will be seen that by my invention, the pneumatic bulb is in close proximity to the 20 slit or nozzle from which the powder emerges, so that the rubber conduit is short and the chance for leakage correspondingly small. The plunger is an ordinary rod actuated by simple pressure with the palm, as 25 indicated in the drawings, affording an effective compression of the bulb and a correspondingly strong blast to form a sharp and distinct line, which will be distinctly visible not only upon dark woolen goods but 30 also upon silks or satins of light shades. If instead of the use of a plunger for actuating the device, the hand-pressed pneumatic bulb is used and if such bulb is at a sufficient elevation to be conveniently grasped by the 35 hand without bending down, it is apparent that a relatively long conduit would connect the bulb to the nozzle so that a materially greater volume of air would be enclosed than in my construction. As is obvious from 40 elementary principles of physics, the compression of the bulb by the hand would consequently increase the pressure of the confined air less than in my construction, so that the force with which the powder would 45 be ejected through the slit would be lower and the line would not ordinarily have the required sharpness and distinctness for practical purposes, particularly if applied to light-colored silk skirts. It is, moreover, to 50 be observed that the process of reaching for a bulb, grasping it and pressing it hard repeatedly in making the line will tire the muscles of the hand and forearm while, by my invention, the simple application of 55 downward pressure with the palm constitutes no effort, but on the contrary, actually tends to rest the hand.

A single filling of chalk is sufficient to 60 mark many dozens of skirts. When the supply of chalk is exhausted, the plunger is depressed, the nozzle slit 15 placed under the surface of powdered chalk in a box and upon allowing the plunger to rise, it is apparent that chalk will be sucked into the 65 bulb to substantially fill the same, in a man-

ner similar to the filling of a dropper or syringe.

It will thus be seen that there is herein described apparatus in which the several features of this invention are embodied, and which apparatus in its action attains the various objects of the invention and is well suited to meet the requirements of practical use.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

I claim:—

1. In a skirt marker, in combination, a support having a scale, a marking unit adjustably mounted on said scale, said marking unit including a chamber lodging a powder-containing bulb, a nozzle carried by said unit, a conduit connecting said bulb to said nozzle, a presser for said bulb and a plunger conveniently operable by a standing person for operating said presser to cause the ejection of powder from said nozzle.

2. In a skirt marker, in combination, a support having a scale, a marking unit adjustably mounted on said scale, said marking unit including a chamber lodging a powder-containing bulb, a nozzle carried by said unit, a conduit connecting said bulb to said nozzle, a presser for said bulb, and a plunger rigidly connected to said presser and guided to travel parallel to said scale and conveniently operable by a standing person to cause the ejection of powder from said bulb through said nozzle.

3. In a skirt marker, in combination, a support having a scale, a marker unit adjustably mounted on said support, said marker unit including a chamber containing an elastic powder enclosing bulb, a nozzle formed integral with said chamber, a conduit connecting said bulb to said nozzle, a presser to engage said bulb, said presser extending from the exterior through an aperture in said casing, and an operating rod conveniently accessible to a standing person for actuating said presser.

4. The combination set forth in claim 8 in which the effective end of the presser is wider than the casing aperture through which it extends.

5. In a skirt marker, in combination, a marking unit comprising a casing member having integrally formed at one edge thereof a tubular conformation having a longitudinal slit, a powder containing bulb within said chamber and a duct connecting the mouth of said bulb to an end of said tubular conformation.

6. In a skirt marker, in combination, a marking unit comprising a sheet metal casing element having formed integrally therewith a tube of small diameter extending 5 along one edge thereof and having a longitudinal slit, a powder-containing bulb lodged in the interior of said casing and a conduit extending on the exterior of said casing and connecting the mouth of said bulb to one end of said tube.
7. A skirt marker comprising in combination, a vertical member having a scale, a casing element adjustably clamped with respect thereto including a nozzle and enclosing 15 a bulb containing marking powder and communicating with said nozzle, and a presser element connected to said second member and extending through a slot in said casing for pressing upon said bulb.
8. A skirt marker comprising in combination, a bar having a scale, a plunger rod for movement parallel to said bar and having operating means at its upper end, a marking unit adjustably secured with respect to said 20 bar and enclosing a powder container and including a nozzle communicating with said powder-container, and a presser to act upon said powder-container for effecting the mark, said presser being connected to said plunger 25 rod to be operated thereby.

9. In a skirt marker, in combination, a stick having a graduated scale, a second stick slidably arranged with respect to said first stick, a marking unit adjustably clamped with respect to said first stick and comprising a casing including a nozzle and enclosing a powder-containing bulb communicating with said nozzle, and a presser for said bulb extending through a slot in said casing and connected to said upper stick. 35

10. The combination set forth in claim 9 in which the presser constitutes a sheet metal blank secured to the upper stick and has a toe in surface engagement with the bulb. 40

11. A marking unit comprising in combination, a sheet metal casing enclosing a powder-containing bulb, said casing having a slotted tube formed integral therewith and extending transversely thereof, a conduit connecting the mouth of said bulb to an end of said tube, said casing having integral therewith a longitudinal collar at right angles to said tube to be passed over a bar and a clamping screw in a side of said collar for clamping said casing in position. 50

Signed at New York in the county of New York and State of New York this 15th day of August A. D. 1921.

RUDOLF WASSERMAN.
